UNITED STATES PATENT OFFICE

WILLIAM M. GRIFFIN, OF FORT WAYNE, INDIANA, ASSIGNOR TO WAYNE COMPANY, OF FORT WAYNE, INDIANA, A CORPORATION OF INDIANA

DESIGN FOR A FLUID DISPENSING APPARATUS

Application filed January 21, 1933. Serial No. 46,920. Term of patent 7 years.

To all whom it may concern:

Be it known that I, WILLIAM M. GRIFFIN, a citizen of the United States, residing at Fort Wayne, in the county of Allen and State of Indiana, have invented a new, original, and ornamental Design for a Fluid Dispensing Apparatus, of which the following is a specification, reference being had to the accompanying drawing forming a part thereof.

Figure 1 is a front elevation of the article showing my new design, the device being substantially the same on the opposite side thereof; and

Figure 2 is a side elevation of the article shown in Figure 1.

I claim:

The ornamental design for a fluid dispensing apparatus as shown and described.

WILLIAM M. GRIFFIN.
